ATTORNEY

UNITED STATES PATENT OFFICE.

PETER SCHNEIDER, OF BROOKLYN, E. D., NEW YORK.

ASPERSORIUM.

SPECIFICATION forming part of Letters Patent No. 250,398, dated December 6, 1881.

Application filed May 20, 1881. (No model.)

To all whom it may concern:

Be it known that I, PETER SCHNEIDER, a citizen of the United States, residing at Brooklyn, E. D., in the county of Kings and State of New York, have invented a new and useful Aspersorium, of which the following is a specification.

The object of my invention is to provide an aspersorium having a body composed of non-corrosive material with a handle adapted to be applied to and attached to the said body after the same is formed and finished.

The invention consists in providing the non-corrosive body with a flaring neck to receive and retain a metallic band placed around the said neck and conformed to it so as to be prevented from slipping off, said band furnishing a connection for the handle of the aspersorium.

It also consists in the arrangement for connecting the band with the neck, hereinafter described.

In the accompanying drawings, Figure 1 represents a side elevation of my improved aspersorium. Fig. 2 is a sectional view of the top, 25 showing the handle connection; and Fig. 3 is a top plan of the aspersorium. Fig. 4 represents, on an enlarged scale, a sectional elevation of the connection of the ears with the band and the top of the aspersorium.

Referring to the drawings, A represents the body of the aspersorium, which may be made of glass, crystal, or other suitable material not subject to corrosion or depreciation by the action of water or the atmosphere. The body 35 may be made of any suitable shape and color, and it may be ornamented with sacred and other symbols. The top B is turned outward, forming an outwardly-flaring neck, a. An annulus or band, C, is conformed circumferentially to the neck a by giving it a downwardly and inwardly inclined bevel, as shown, so that when placed around the neck the latter will hold it securely in connection with the body A. As the aspersorium must be finished after

being formed in the mold the band has to be 45 adapted to be placed on the neck after it is taken out of the mold. For this purpose the band is formed of one, two, or more open pieces, which are placed around the neck and connected therewith by soldering the ends together, or by splicing them by means of plates *d*, interposed between the band and the neck and soldered or riveted to the ends, as shown.

E E represent the ears to which the handle F is swung. These ears may be attached directly to the band C, or they may be attached to the splicing-plates *d* by passing the studs or pins *b* on their inner ends through the plates *d* and riveting or otherwise fastening them to the said plates.

An aspersorium made of a non corrosive material has many advantages over those heretofore used, which, being made of metal, are quickly corroded by the water and atmosphere, and in turn contaminate the water. They also 65 become offensive to the sight and touch; but by making the body or reservoir of glass and similar materials corrosion is impossible, they are elegant in appearance, clean to handle, and are much more economical than when made 70 of metal. By providing the top with a beveled or flared neck the band which connects the handle to the body or reservoir is prevented from slipping off, and by making the band in parts and connecting the ends in the manner 75 described the body can be finished before the band and handle are put on.

I claim—

The combination of the non-corrosive body A, flaring neck *a*, band C, splicing-plates *d*, 80 ears E, provided with studs *b*, attached to plates *d*, and handle F, substantially as shown and described.

PETER SCHNEIDER.
